CLAIM

The ornamental design for a fly strip, as shown and described.

DESCRIPTION

FIG. 1 is a perspective view of a fly strip showing my new design;

FIG. 2 is a right side view, the left side being a mirror image thereof;

FIG. 3 is a top plan view, the bottom plan view being a mirror image thereof;

FIG. 4 is a front elevational view;

FIG. 5 is a rear elevational view;

FIG. 6 is a perspective view;

FIG. 7 is a rear perspective view; and,

FIG. 8 is perspective view.

The broken line showing of environment in FIGS. 6-8 is for illustrative purposes only and forms no part of the claimed design.
